UNITED STATES PATENT OFFICE.

CHARLES H. LAWTON AND HIRAM H. STONER, OF WABASH, INDIANA.

DESIGN FOR A SIGN-POST.

SPECIFICATION forming part of Design No. 26,079, dated September 22, 1896.

Application filed July 23, 1896. Serial No. 600,310. Term of patent 7 years.

To all whom it may concern:

Be it known that we, CHARLES H. LAWTON and HIRAM H. STONER, citizens of the United States, residing at Wabash, in the county of 5 Wabash and State of Indiana, have invented and produced a new and original Design for a Sign Post and Board, of which the following is a specification, reference being had to the accompanying drawings, showing a part 10 thereof.

In the accompanying drawings, forming a part of our specification, Figure 1 is a front elevation of a post and sign, showing our design. Fig. 2 is a plan.

15 Numeral 1 denotes a base comprising arms 2, having each of their ends enlarged, as represented, the inner ends being joined, as shown, at the center of the base. 3 denotes a slender post standing on said center.

20 4 indicates braces, which suggest the idea

of stability and constitute, in ornamental effect, a part of the base.

The post 3 is surmounted by an ornamental terminal 5.

6 denotes a sign-board comprising arms 25 provided with fingers 7.

8 indicates a series of holes in the board, which are visible on both sides.

Having thus described our invention, what we desire to claim and secure by Letters Patent is—

The design for a sign-post herein shown and described.

In testimony whereof we affix our signatures in presence of two witnesses.

CHARLES H. LAWTON.
HIRAM H. STONER.
